UNITED STATES PATENT OFFICE.

STONEWALL JACKSON CAROLAND, OF CLARKSVILLE, TENNESSEE.

HOOP-DRAWING APPARATUS.

No. 839,452.

Specification of Letters Patent.

Patented Dec. 25, 1906.

Application filed October 19, 1905. Serial No. 283,517.

To all whom it may concern:

Be it known that I, STONEWALL JACKSON CAROLAND, a citizen of the United States, residing at Clarksville, in the county of Montgomery and State of Tennessee, have invented a new and useful Hoop-Drawing Apparatus, of which the following is a specification.

This invention relates to the production of wooden hoops for hogsheads, barrels, and the like, and has for its object to provide an improved device of this character which is arranged to facilitate the drawing therethrough of the stock, so as to trim the latter on opposite sides to the desired thickness in a very simple and expeditious manner.

A further object of the invention is to enable the satisfactory flattening or skiving of one end of the hoop without stopping the movement of the material through the apparatus. It is also proposed to provide for effectually guiding the work to the knives and to have the apparatus under the complete control of the attendant.

With these and other objects in view the present invention consists in the combination and arrangement of parts, as will be hereinafter fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a top plan view of a hoop-drawing apparatus of the present invention. Fig. 2 is a longitudinal sectional view thereof. Fig. 3 is a cross-sectional view on the line 3-3 of Fig. 1. Fig. 4 is a detail perspective view of one of the knife-adjusting wedges.

Like characters of reference designate corresponding parts in all of the figures of the drawings.

The present device includes a base or body 1, which is rigidly secured upon the top portion 2 of a suitable frame or stand, the latter being considerably longer than the body or the base, so as to support the work during its progress through the apparatus. The top 2 is supported adjacent its opposite ends upon posts 3 and 4, so as to support the apparatus at a conveniently accessible height. At what will be termed the "forward" end of the body or base the latter is provided with

an opening 5, in which is received a pair of upstanding knife-blades 6, each of which is substantially triangular in cross-section and has its cutting edge directed toward the rear of the device. Rearwardly and downwardly inclined braces 7 extend between the tops of the knives and the base or body 1, there being a bolt 8 piercing the tops of the knives and the braces, so as to connect these members.

As best indicated in Fig. 1 of the drawings, it will be noted that the outer faces of the knife-blades are beveled or inclined, while their adjacent faces are substantially parallel, there being upper and lower spacing-blocks 9 interposed between the knife-blades. Each of these spacing-blocks is preferably wedge-shaped, as clearly indicated in Fig. 4 of the drawings, and has a longitudinal slot 10. The bolt passes through the slot of the upper spacing-block, and another bolt 11 pierces the lower end portions of the knife-blades and passes through the slot of the lower spacing-block and also transversely through the base or body 1. By driving the wedges the spacing of the knife-blades may be regulated according to the desired thickness of the hoop to be drawn. In addition to the braces 7 there are also braces 12, which incline downwardly and outwardly from the tops of the knife-blades to the base or body 1 and are pierced at their upper ends by the bolt 8, whereby the knife-blades are rigidly supported in a simple and convenient manner.

In front of the knife-blades there is a work-guide made up of a pair of longitudinally-disposed flat spring-bars 13, which are terminally pivoted to the base or body 1, as at 14, from which they converge toward the knife-blades and have their free ends provided with antifriction-rollers 15. About midway between the ends of these guide members there is an arched bar 16, straddling the members and pierced through its opposite sides by set-screws 17, which are designed to bear against the respective guide elements to maintain the necessary tension thereon. A stop-arch 18 is carried by the base or body and interposed between the guide members 13. Still another arch 19 straddles the guide members 13 between the arch 16 and the knife-blades, so as to prevent upward displacement of the work.

Immediately in front of the knife-blades

the base or body 1 is provided with an opening 20, there being an opening 21 formed through the top 2 of the stand and registering with the opening 20. Working in the opening 20 is an upstanding yoke or fork 22, the bottom of which normally rests against shoulders 23, formed in the opening 20, so as to limit the downward movement of the fork. A stem or bar 24 depends from the fork through the openings 20 and 21 and has its lower end pivotally connected to the adjacent end of a foot-lever 25, fulcrumed in an opening 26 in the adjacent post 3. A suitable tension device is employed for yieldably holding the fork 22 at its lower limit—such, for instance, as a weight 27, carried by the rod or stem 24.

In practice the work, which is a strip of wood of suitable length—say fourteen or fifteen feet—is placed edgewise upon the base or body 1 between the guide members 13 and is pushed therebetween and also between the knife-blades, the forward end of this wooden strip having been thinned or tapered by means of an adz or other implement, so as to enable the convenient passing of the forward end of the strip between the knife-blades. After thus being set a suitable clamp (not shown) is connected to the forward end of the work, and a single horse or a team is hitched to the clamp and driven away from the apparatus, so as to draw the strip of wood between the knife-blades, which latter shave off opposite sides of the strip and reduce the latter to the desired thickness.

By reference to Fig. 3 of the drawings it will be noted that the knife-blades are set to converge upwardly, and when the rear end of the work approaches the knives the attendant pressure downwardly upon the foot-lever 25, so as to elevate the fork 22, whereby the rear end portion of the work will be elevated between the knife-blades, and by reason of the upward convergence of the knife-blades the rear end portion of the work will be reduced in a very simple and efficient manner. During the passage of the work through the apparatus it is held against upward displacement by the arch 19, and therefore the fork 22 can be elevated only when the rear end of the work has cleared the arch 19. In other words, the arch 19 acts as a gage to hold the work in lowered position until the end of the work moves out from under the arch 19, after which the fork 22 is operated to elevate the work, whereby to reduce the extreme end thereof.

When the work is passing between the knives, each knife of course trims or cuts a shaving from the adjacent side of the work, and therefore a shavings-deflector 28 is provided at the outer side of each knife with its lower end portion secured to the body or base 1, as at 29, and its upper end pierced by 65 the fastening 8. The purpose of these de-

flectors is to direct the shavings outwardly, and thereby prevent choking of the knife-blades.

To accommodate the device to work of different thicknesses, it is proposed to provide wedges 9 of different sizes, and by the provision of the slot 10 each wedge may be driven in between the knife-blades, so as to obtain slight adjustments of the latter without requiring the substitution of a wedge of a different thickness. By preference a branch slot 10' intersects one edge of the wedge and the slot 10, so as to enable the engagement of the wedge with the adjacent bolt without removing the latter.

While it is not absolutely necessary, I propose to employ upstanding guide-rollers 30, carried by the base or body 1 and spaced at opposite sides of the path of the work as it passes between the knives 6, whereby any lateral strain of the power upon the work will not tend to wedge the latter against one of the knives. The upper ends of the guide-rollers are journaled in brackets 31, carried by the tops of the respective deflecting elements 28.

Having thus described the invention, what is claimed is—

1. A device of the class described comprising a pair of spaced knife-blades, having their cutting edges converged, a fastening piercing the blades, and adjustable wedges fitted between the blades and pierced by the fastening.

2. A device of the class described comprising a pair of spaced knife-blades, removable fastenings piercing the blades, and removable wedges interposed between the blades and pierced by the fastenings.

3. A device of the class described comprising a pair of spaced knife-blades, spaced fastenings piercing the blades, and wedges interposed between the knife-blades and pierced by the fastenings, each wedge being provided with a slot to permit driving of the wedge across the fastening.

4. A device of the class described comprising a pair of knife-blades, a pair of spaced spring guide-arms leading to the knife-blades, an arch spanning the guide-arms, set-screws piercing the arch and engaging the respective guide-arms, and a second arch spanning the arms adjacent their free ends and acting as a gage for the work.

5. A device of the class described comprising a pair of knife-blades, a pair of pivotally-spaced spring guide-arms having their free ends converged toward the knife-blades, an arch spanning the guide-arms, set-screws piercing the arch and engaging the guide-arms, and a second arch spanning the arms adjacent their free ends and acting as a gage for the work.

6. In a device of the class described, the combination with a pair of knife-blades hav-

ing their cutting edges disposed mutually adjacent and converged, of a work-receiving vertically-movable fork located in front of the knives and adapted to have the work travel thereover, and means to shift the fork longitudinally of the knives in the direction of their convergence.

7. In a device of the class described, the combination with a pair of knife-blades having their cutting edges disposed mutually adjacent and converged, of a vertically-shiftable work-receiving member located in front of the knives and adapted to have the work travel thereover, and a foot-lever for elevating the work-receiving member.

8. In a device of the class described, the combination with a frame, of a pair of knife-blades carried thereby with their cutting edges disposed mutually adjacent and converged, a vertically-shiftable work-receiving

element mounted upon the stand and having a depending stem, and a foot-lever fulcrumed upon the stand and connected to the stem for elevating the work-receiving element.

9. A device of the class described comprising a pair of spaced knife-blades, a fastening piercing the blades, and a removable wedge interposed between the blades and provided with a longitudinal slot receiving the fastening, the wedge also being provided with an entrance-slot leading to the longitudinal slot.

In testimony that I claim the foregoing as my own I have hereto affixed my signature in the presence of two witnesses.

STONEWALL JACKSON CAROLAND.
